UNITED STATES PATENT OFFICE.

GREGORIO JOHN BOONZAIER AND SIDNEY HARTLEY, OF LONDON, ENGLAND, AS
SIGNORS TO BRITISH & COLONIAL INVENTIONS LIMITED, OF E. C. 4, ENGLAND.

PUMP OR COMPRESSOR.

Application filed June 4, 1924, Serial No. 717,745, and in Great Britain December 8, 1923.

The present invention relates to improvements in pumps or compressors of the reciprocating type in which ports or openings arranged in the piston are adapted to co-operate with other ports in the wall of the cylinder or casing, thus doing away with the use of poppet, slide or other valves or controlling means.

In addition to its reciprocating movement, the piston is, according to the invention, given a continuous rotary motion in one direction about its longitudinal axis, thus avoiding the drawbacks and loss of efficiency usual with that type of pump or compressor, in which the valve piston has a rotary oscillating movement, such as is described in the specification of Boonzaier's Patent No. 1,438,691 granted December 12, 1922.

In constructing a pump of the double-acting type, the piston consists of a cylinder open at both ends, and having a central cross diaphragm or wall to which the piston rod is attached, thus forming two chambers having their openings arranged in opposite directions. The wall of each chamber is provided with a port or ports which may be of rectangular shape or of a spiral or other shape, adapted to come into alignment with the inlet port or ports or outlet port or ports of the pump cylinder or casing as the piston is reciprocated and rotated therein.

The ports in the upper and lower halves of the piston are so arranged as to produce the desired opening of the suction port in the cylinder and the closing of the delivery port in the necessary sequence.

Generally the cylinder or casing will be provided with a suction port on one side and a delivery port on the diametrically opposite side, while each piston chamber will have one port, although the piston may have three or other odd number of ports, at equal distances apart in some cases; for example, if the piston has three ports they will be spaced apart at 120° each, whereas if it is provided with five ports they will be at 72° .

The number of reciprocations of the piston relatively to one complete rotation thereof, will be arranged in accordance with the number of ports in the piston, and the following formula may generally be adopted, i. e. the number of complete reciprocations of the piston to one complete rotation of piston will be equal to the sum of half the number of ports in the casing multiplied by the number

of ports in the piston, (or in the one end of the piston only in the case of a double acting pump).

The reciprocating motion of the piston may be obtained by means of a crankshaft, or the piston may be driven direct from the steam chest of the motor engine, or other means, such as a cam, working on the piston or connecting rod, or an extension thereof may be employed for that purpose, the arrangement being such, however, that continuous rotation of the piston is provided for.

This rotation may be effected by means of a bevel wheel, mounted on the piston rod and driven by bevel gearing on the driving shaft or crankshaft, the connection of the bevel wheel to the piston rod being such that its reciprocating motion will not be interfered with.

While we have referred to the rotary motion of the piston as being effected by bevel gearing, it may also be effected by means of combined bevel and spur gearing, by combined crown wheel and spur gearing, by combined bevel gearing and chain, by chain gearing, by worm and worm wheel, or by a cam device or other suitable means, and one or other of the above means may be also employed to obtain the reciprocating motion.

The accompanying drawings illustrate examples of the construction and of the functioning of apparatus embodying the invention.

Fig. 1 shows a double-acting vertical surface pump, driven by a crank shaft, in side elevation, and

Fig. 2 is a vertical section of the same on the line 2—2 of Fig. 1.

Fig. 3 is a cross section on the line 3—3 of Fig. 2.

Fig. 4 is a cross section on the line 4—4 of Fig. 2.

Fig. 5 is a similar section on the line 4—4 of Fig. 2 when the piston is at the top end of its stroke.

Fig. 6 is a cross section on the line 6—6 of Fig. 2, but assuming the piston to be in the middle of a stroke.

Fig. 7 shows diagrammatically, in cross sections and their development, the different relative positions of the piston ports to the suction and delivery ports during a double stroke of the pump shown in Figs. 1—6 in which the ratio of a double stroke to the

rotary motion of the piston is one to one, while

Fig. 8 is a similar diagram showing cross sections only of the relative positions of the piston and cylinder ports during half a revolution of the piston in a pump in which the piston is adapted to perform three complete double strokes while effecting one revolution.

Fig. 9 shows the head of a pump having its driving gear connected directly to the piston rod of a steam or other engine.

In the double-acting surface pump illustrated in Figs. 1 to 6, the cylinder is constituted by a casing 1, the bore of which has a length substantially three times the length of the piston stroke. Centrally of its length the cylinder is provided with diametrically opposite ports: a suction port A and delivery port B, both of substantially rectangular shape and having an axial length rather exceeding the piston stroke.

In the part of the cylinder extending above the ports A and B, a closed cylindrical inward projection 3 of a top cover 4 forms an annular recess 2 in the cylinder, the inner flat face of said projection, which is in alignment with the top edges of the ports A and B, constituting the upper limit of the working chamber C which is thus situated diametrically across the cylinder between the said ports. The bottom of this working chamber C is formed by a cushion of the fluid which, in the working of the pump, fills the lower part of the cylinder below the ports A and B. Incidentally, in the case of a pump, this pocket also functions as a sump in which sand or other solid matter may settle.

The piston 5 is provided at both sides with hollow cylindrical extensions or skirts 5^a and 5^b, fitting the bore of cylinder 1, and of a length slightly exceeding the length of stroke.

The skirt 5^a is provided with an aperture or piston port a and the skirt 5^b with a similar aperture or piston port a', the two piston ports being arranged at diametrically opposite sides of the skirts 5^a and 5^b.

The piston 5 is secured to the piston rod 6, which is adapted to rotate and slide axially within a sleeve 3^a, formed centrally in the projection 3 of the top cover 4.

The driving gear is mounted on a support or pedestal 7 supported on the top of the cylinder 1. The pedestal 7 carries, preferably formed integrally therewith, a pair of vertical guide rails 8 for a crosshead 9, from the lower end of which the end 6^a of

the piston rod 6 is rotatably suspended. Transverse beams 10 rigidly secured to the guide rails 8 so as to provide lateral guidance for the cross-head 9, form the bearings for a cranked driving shaft 11, which, when actuated in any convenient manner, imparts

reciprocating motion to the crosshead 9 by means of its crank 11^b and connecting rod 12, which latter is connected to the crank pin 11^a and the wrist 9^a of the cross head 9.

In order to reduce the height of the driving gear and thereby of the pump, the cross-head 9 is preferably formed as a yoke embracing the crank 11^b and the connecting rod 12, as shown.

A continuous rotary motion is transmitted to the piston 5 from the driving shaft 11 by means of bevel gears 13, 14. The gear 13 is mounted on the shaft 11, while the gear 14 is mounted on a squared portion 6^b of the piston rod 6, this arrangement allowing the latter to slide axially in the wheel 14, which is rotatably journaled but secured against axial displacement in a bearing 15 arranged in the top plate 7^a of the pedestal 7. The reciprocating as well as the continuous rotary motions of the piston 5 are thus derived from the same source viz. from the crank shaft 11.

In the example illustrated in Figs. 1 to 7, these motions are transmitted at the ratio of 1 to 1, that is to say, the piston is caused to execute one complete revolution to every revolution of the crank or to every double stroke of the piston.

The ports of the piston skirts 5^a and 5^b are so positioned angularly in relation to the suction port A and the diametrically opposite delivery port B that complete closure of all ports is co-incident with the end of each single stroke of the piston, while the area open, both on the suction side A and on the delivery side B, reaches its maximum at the middle of each individual (up or down) stroke.

The opening and closing of the ports at various stages in the course of a complete double stroke as performed by the pump hereinbefore described in connection with Figs. 1 to 6, is illustrated in the diagrams comprising Fig. 7, in which the axial as well as the radial positions of the piston and its ports are shown not only in developments of the contacting surface of the cylinder 1 with the piston skirts 5^a and 5^b, but also in cross sections. These cross sections, being intended to show the angular relative positions only of the piston and cylinder ports, are taken, as regards the cylinder, centrally through the suction and delivery ports, and, as regards the piston, through the upper and lower piston skirts on planes above and below the piston 5 respectively, without regard to the axial relative positions of the piston and the cylinder.

In these diagrams, that is to say, in the developments of the cylinder and the piston walls, the uncovered portions of the cylinder wall are shaded by vertical lines, while those portions of the suction and delivery ports A and B which, at the various stages illus-

trated, are in communication with the piston ports, are shown by vertically and horizontally crossed hatching representing suction and diagonally crossed hatching representing delivery.

If the position D, the piston is represented at the top of its stroke, while D', D² and D³ show the position of a down stroke; D² thus representing the piston at the middle of its stroke. After performing the last quarter of its down stroke, the piston arrives at the bottom end of its stroke represented in the diagram at U, from which position the piston in its up stroke successively passes through the positions U', U² and U³ (each of which again illustrates the positions at the completion of successive quarter strokes) back to the position shown at D.

By following the piston on its down stroke (positions D', D², D³) it will be seen that the piston port a', which is in front as regards the direction of movement of the piston 5, co-operates with the delivery port B, while the piston port a, in the rear as regards the direction of movement of the piston 5, co-operates with the suction port A, and that on the up stroke (positions U', U², U³) the function of the piston ports a' and a in relation to the ports A and B is reversed.

By comparing the positions D and U, which represent the piston at the beginning of each single down or up stroke respectively it will be clearly seen that in the course of each stroke (whether up or down) the piston has simultaneously performed one half of a revolution.

As will further be seen from these diagrams, all ports are closed at the end of each stroke, that is during the reversing of the reciprocatory motions of the piston, are gradually opened in the first half of the stroke until at the middle of the stroke the piston ports register to their full width with the cylinder ports, and are gradually closed again in the second half of the stroke.

It is obvious that the piston may perform more than one complete double stroke during one revolution. If the desired ratio between the reciprocating (double stroke) and the rotary motions of the piston be, for example, three to one, the bevel wheel 14 or other suitable gear wheel may be driven by an intermediate speed reducing gear, so that while the gear 14 and, consequently, the piston effect one revolution, the shaft 11 and, consequently, its crank 11^p perform three revolutions, thus causing the piston to execute three complete double strokes, or six single strokes. In this case, one double stroke being performed by the piston during one third of a revolution thereof, each of the piston skirts 5^a and 5^b will be provided with three ports, which are successively brought into co-operation with the diametrically opposite suction

and delivery ports A and B respectively of the cylinder.

Fig. 8 illustrates diagrammatically the co-operation in such an arrangement of the piston and cylinder ports (as regards their relative angular positions only however), which are shown by cross-sections through the cylinder 1 and through the piston sleeves 5^a and 5^b, no consideration being given in the diagrams to the axial relative positions of such ports.

The piston skirts 5^a and 5^b are each provided with three ports a, b, c, and a', b', c' respectively, arranged at 120° in each skirt and at 180° as regards the ports of the two skirts, thus constituting three pairs of ports a, a', b, b' and c, c' which will be brought successively into operation in successive strokes of the piston.

Fig. 8 shows the relative positions of the piston and cylinder ports from quarter to quarter stroke through three single strokes and a simultaneous half revolution of the piston.

As will be seen, starting from the top on the down stroke, the piston ports a and a' co-operate with the suction and delivery ports A and B respectively, while on the following up stroke the port b opens to the delivery port B and the port b' to the suction port A, the ports c and c' being brought at the end of the up stroke into a position whereby they are rendered operative on the succeeding down stroke in connection with the ports A and B respectively. As will be seen in the last of the series of positions shown, the ports a and a' are now again ready for co-operation, on the following up stroke, with the delivery side B and the suction side A respectively. Similarly the ports b, b' and c, c' will be brought into action in the succeeding down and up strokes respectively, after which the performance is similarly repeated in every succeeding six strokes of the piston. Each set of piston ports will thus be operative on every third stroke of the piston alternately on a down stroke and on an up stroke and also alternately in co-operation with the suction port and the delivery port.

As has been shown in the examples hereinbefore described, the number of ports in each piston skirt, when using one suction and one delivery port in the cylinder, is equal to the ratio of the number of reciprocations of the piston to the revolutions thereof, with the reservation however, that said number of piston ports and ratio must always be an odd number. The reason for this reservation is to be found in the following considerations.

Obviously, the two diametrically opposite cylinder ports (suction and delivery) must never be opened simultaneously to the ports on one side or skirt of the piston, i. e. no two

ports in the same piston skirt must be diametrically opposite each other. At the same time the fact that the strokes of the piston are always of uniform length and duration, necessitates an equidistant distribution of the piston ports over the circumference thereof. A fulfilment of these two conditions is only possible by the arrangement of an odd number of ports in each piston skirt.

Fig. 9 shows an arrangement in which the pump is directly coupled to and operated by the piston rod 17 of a steam or other engine which is connected in any suitable manner, such as for instance, by bolting a crosshead 17^a of the piston rod 17 to flanges 9^c provided on the crosshead 9 of the pump gear.

The piston rod 6 of the pump thus receives its reciprocating movements directly, through the intermediary of the crosshead 9, from the said engine, while it is now the crosshead 9 which, through the connecting rod 12 and the crank 11^b, imparts rotary motion to the shaft 11 from which such rotary motion is transmitted at the desired ratio, for instance, by means of the bevel gear 13, 14 or other suitable or reducing gear, to the piston rod 6 of the pump in the manner hereinbefore described.

While the foregoing description has reference to a double-acting pump, the simple omission of one of the piston skirts renders the pump a single-acting one, in which obviously the length of the cylinder may be reduced so as slightly to exceed only the double length of the stroke. In all other respects, including the arrangement and number of piston ports, the single acting pump may be arranged in the same manner as the double acting pump hereinbefore described.

In some cases, particularly where the apparatus is to be used for the compression of air or the like, we may, instead of providing the piston with open ended skirts, form the said piston as a solid member or as a hollow member with closed ends. In such an arrangement, the piston ports will then be constituted by grooves or channels formed in the outer surface of the piston and extending longitudinally of the same; for example, in the case of a double-acting piston making one complete double stroke per revolution, there will be two diametrically opposite grooves, one extending substantially from the top to the middle of the piston in an axial direction, and the second diametrically opposite groove extending substantially from the middle to the bottom thereof.

By reversing the direction of rotation of the crank shaft 11 the pump will operate in an analogous manner in the opposite direction.

What we claim is:—

1. A pump or compressor, comprising a cylinder provided with suction and discharge ports; a reciprocatory cross-head; operating means therefor; a piston rod rotatably suspended from said cross-head to move up and down therewith; a piston attached to said rod for controlling the cylinder ports during its movements; a gear wheel mounted on the piston rod but held against reciprocatory movement therewith; and means for rotating said gear wheel and thereby the piston rod and piston during their reciprocation with the cross-head.

2. A pump or compressor, comprising a cylinder provided with suction and discharge ports; a reciprocatory cross-head; operating means therefor; a frame wherein the cross-head is slidably mounted; a piston rod rotatably suspended from said cross-head to move up and down therewith; a piston attached to said rod for controlling the cylinder ports during its movements; and gearing for rotating the piston rod and piston during their reciprocation with the cross-head and including a gear rotatably mounted in said frame and with which said rod is slidably engaged.

3. A pump or compressor, according to claim 2, in which the piston rod is engaged with the frame-mounted gear in a manner to rotate with that gear and to slide axially through the same during such rotation.

4. A pump or compressor, comprising a cylinder provided with suction and discharge ports; a crank shaft rotatably mounted above said cylinder; a cross-head connected to said shaft to be reciprocated thereby; a frame wherein the cross-head is slidably mounted; a piston rod rotatably suspended from said cross-head and having a portion of polygonal section; a piston attached to said rod for controlling the cylinder ports during its movements; a gear rotatably fixed to said frame and having a polygonal opening through which the polygonal portion of the piston rod slidably extends; and means for rotating said gear, and with it said piston rod and piston, during the rotation of the crank shaft.

In testimony whereof we affix our signatures.

GREGORIO JOHN BOONZAIER.
SIDNEY HARTLEY.
